UNITED STATES PATENT OFFICE

163,116

SLIDABLE SIGNAL FOR VISIBLE INDEX RECORD DEVICES

Marchand B. Hall, Chicago, Ill., assignor to
Acme Visible Records, Inc., Chicago, Ill., a cor-
poration of Delaware

Application April 20, 1949, Serial No. 2,156

Term of patent 14 years

(Cl. D74—1)

To all whom it may concern:

Be it known that I, Marchand B. Hall, a citizen of the United States, residing at Chicago, in the county of Cook and State of Illinois, have invented a new, original, and ornamental Design for a Slidable Signal for Visible Index Record Devices, of which the following is a specification, reference being had to the accompanying drawing, forming part thereof.

Figure 1 is a perspective view of a slidable signal, showing my new design;

Figure 2 is a front elevational view of the same; and

Figure 3 is a top plan view of the same.

The essential features of my design for a slid-
able signal for visible index record devices reside
in the specific configuration thereof consisting of
substantially a straight side, a rounded portion
on the other side gradually widening out toward
the end with two bent over portions on both ends,
all as illustrated.

I claim:

The ornamental design for a slidable signal for
visible index record devices, substantially as
shown and described.

MARCHAND B. HALL.
